AZO DYE

Chiles E. Sparks, Wilmington, Del., assignor to
E. I. du Pont de Nemours & Company, Wil-
mington, Del., a corporation of Delaware

No Drawing. Original application June 25, 1940,
Serial No. 342,289. Divided and this applica-
tion November 14, 1940, Serial No. 365,610

12 Claims. (Cl. 260—154)

This invention relates to new tetrakisazo compounds, to dyeings on cellulosic fibers, such as cotton and regenerated cellulose which are produced with such compounds by dyeing the fibers with a type of di(amino-phenoxy-alkyl-acyl-amino)alkanes, diazotizing and developing in the fiber with suitable coupling components, and to processes of making such compounds and dyeings.

Various disazo compounds having substantivity for cotton and regenerated cellulose and which can be tetrazotized on the fiber and coupled with coupling components to form dyeings of excellent fastness and good insolubility are known; but in many cases the dyeings developed from such substantive tetrazotizable compounds do not have as good brightness as is desired.

It is among the objects of this invention to provide new tetrakisazo compounds. Another object of the invention is to provide developed dyeings of improved brightness, washing fastness, discharge properties and other properties desired in developed dyeings. Other objects of the invention will be apparent from the following description.

The objects of the invention are attained in general by providing a compound which may be made by tetrazotizing one of a class of di-amino-phenoxy-alkyl-acylamino) alkanes and coupling with a class of suitable arylamines. This tetrazotizable disazo compound is substantive to cotton and regenerated cellulose. It is dyed on the fiber, tetrazotized thereon and developed with a suitable azo dye coupling component which is devoid of solubilizing groups to form the finished dyeing. The substantive dyes are represented in general by the formula

has 1 to 6 carbons and is present once to two less than the number of carbons in the ring, and a radical of the diazacycloalkane series having 3 to 6 carbons in the ring and the straight and branched chain alkyl derivatives thereof in which alkyl has 1 to 6 carbons and is substituted in the ring carbons once to twice the number of carbons in the ring; $[\text{C}(\text{R})_2]$ represents the group consisting of straight and branched chain aliphatic radicals wherein R occurs twice as indicated and the symbol R represents like and unlike members of the group consisting of hydrogen and alkyl radicals containing 1 to 6 carbon atoms. Of these aliphatic radicals, there may be 1 to 10 as represented by the subscript n, for example

—[C(R)₂]_n—

includes such radicals as

and

where alkyl may be any saturated aliphatic hydrocarbon radical containing 1 to 6 carbon atoms; "R" is from the group consisting of hydrogen, alkyl with 1 to 6 carbon atoms, alkoxy with 1 to 6 carbon atoms, halogen, CN, carboxy and sulfonic acid; m is 1 to 4; and $-\text{Y}-\text{NH}_2$ is the radical of an amino-substituted coupling component from the group consisting of certain arylamines of the benzene and naphthalene phenyl-amino-naphthol sulfonic acids, amino-

wherein D represents a radical of the groups consisting of the polymethylene diamines having 2 to 10 methylene groups and straight and branched chain alkyl derivatives thereof in which alkyl has 1 to 6 carbons and is substituted in the methylene groups once to twice the number of methylene groups, a radical of the diamino-cyclo-alkane series having 4 to 6 carbons in the ring and ring substituted straight and branched chain alkyl derivatives thereof in which alkyl

phenyl-amino-naphthol sulfonic acids, amino-benzoyl-amino-naphthol sulfonic acids, amino-benzoyl-amino-benzoyl-amino-naphthol sulfonic acids and amino-phenyl pyrazolones.

The invention will be more fully set forth in the following more detailed description which includes examples that are given as illustrative embodiments of the invention and not as limitations thereof. Parts are expressed in parts by weight unless otherwise noted.

Example I

A slurry was made consisting of 143 parts of 1,2-di(4'-amino-phenoxy-acetylarnino)ethane and 2000 parts of water. It was acidified by adding 73 parts of 100% hydrochloric acid as a 30% solution. The mixture was cooled by adding ice to 0° C. and 55 parts of 100% sodium nitrite were then added. Tetrazotization was continued at 0-5° C. for 1/2 hour whilst maintaining a slight excess nitrite.

A slurry containing 295 parts of 2(3'-amino-benzoylarnino)-5-naphthol-7-sulfonic acid and 2000 parts of water was made. An aqueous solution of ammonia in sufficient quantity for complete solution and a slightly alkaline reaction to Brilliant Yellow paper was added and then 7 parts of sodium-bicarbonate were added. The

5 fabric was rinsed in cold water and then put into 2000 parts of water at 20° C. The compound was tetrazotized on the fiber by adding three parts of sodium nitrite and four parts of sulfuric acid to the water and stirring for 15 minutes. The piece was rinsed with cold water and then put into a solution which was made by dissolving one part of beta-naphthol in 2000 parts of water and one-half part of caustic soda. The solution was stirred rapidly while adding the 10 rinsed piece goods and stirring was continued for 15 minutes. The fabric was then rinsed in cold water and dried. The dyeing was a scarlet shade. The dye on the fiber is represented by the formula

solution was cooled to 0° C. and 170 parts of sodium-carbonate were added.

The solution of the tetrazo compound was 40 slowly added to the cold alkaline solution of 2-(3'-amino-benzoyl-amino)-5-naphthol-7-sulfonic acid. The coupling mixture was stirred one hour after the tetrazo mixture had been added whilst an excess of the coupling component was present and alkalinity with sodium carbonate was maintained. The suspension was then heated to 70°-80° C., salted 5% with sodium chloride and filtered. The precipitate was dried at 80°-85° C. in an oven. The dry product had 50

A dye represented by the formula 1,2-di-(4'-amino-phenoxy-acetylarnino)-ethane $\rightleftharpoons$ (1-(3'-aminophenyl)-5-pyrazolone-3-carboxylic acid)₂ was prepared by a procedure similar to Example I except that 180 parts of 1-(3'-amino-phenyl)-5-pyrazolone-3-carboxylic-acid were used instead of 295 parts of 2(3'-amino-benzoyl-amino)-5-naphthol-7-sulfonic acid. The resulting dye was an orange powder, and had properties similar to the substantive compound of Example I. It is represented by the formula

an orange appearance and substantivity for cotton and similar fibers. The product is represented by the formula

When dyed and developed on the fiber with beta naphthol in a manner similar to that described in Example I the dyeing was an orange

shade. The structure of the dye on the fiber is represented by the formula

Example III

A dye represented by the formula 1,4-di(4'-amino-phenoxo-acetyl)-piperazine $\Rightarrow$ [2(4'-amino-benzoylamino)-5-naphthol-7-sulfonic acid]₂ was made by following the procedure of Example I except that 153.5 parts of 1,4-di(4'-amino-

When dyed on cotton fiber and developed with beta naphthol in a manner similar to that described in Example I the dyeing was a red shade. The dye on the fiber is represented by the formula

phenoxo-acetyl)-piperazine was used instead of 143 parts of 1,2-di(4'-aminophenoxy-acetylamino)ethane and 295 parts of 2-(4'-amino-benzoylamino)-5-naphthol-7-sulfonic acid was used instead of 295 parts of 2-(3'-amino-benzoylamino)-5-naphthol-7-sulfonic acid. The product in the form of a dry powder had an orange appearance and its other properties were similar to those of the product of Example I. The product is represented by the formula

The following products were prepared by methods similar to those of the foregoing examples. The properties of these products were in general similar to the products of the foregoing examples except for variations in shade. The shades listed opposite each product are the shades of the dyeings on cotton when developed with the coupling component indicated.

Many other compounds can be used for the first components to make products having properties similar to the foregoing products which are represented by the general formula heretofore given. As representative of such first components, the following are mentioned:

1,2-di(4'-aminophenoxy-acetylarnino)-ethane,
1,6-di(3'-aminophenoxy-acetylarnino)-hexane,
1,2-di(4'-amino-2'-chloro-phenoxy-acetylarnino)-ethane,
1,2-di[alpha-(4'-amino-2'-methoxy-phenoxy)-propionylaminol]-propane,

1,3-di[alpha(3'-amino-phenoxy)-butyrylaminol]-butane,
65 1,4-di(4'-aminophenoxy-acetyl)-piperazine,
1,2-di(3'-aminophenoxy-acetyl)-3,5-dimethyl-pyrazolidine,
1,4-di(4'-aminophenoxy-acetyl)-ethylene-trimethylene-diamine,

70 1,5-di(3'-aminophenoxy-acetyl)-bis-trimethylene-diamine,
1,4-di(4'-amino-phenoxy-acetylarnino)-butane,
1,10-di[alpha-(4'-amino-phenoxy-propionylaminol)-]decane,

1,3-di(alpha(3'-amino-phenoxy-heptanoylamino)-1-propane,
 1,3-di(beta(3'-amino-phenoxy-butyrylamino)-1-heptane,
 1,2-di(4'-amino-2'-sulfo-phenoxy-acetylamino)-ethane,
 1,2-di(4'-amino-phenoxy-acetylamino)-1,2-dimethyl-ethane,
 1,2-di(beta-(4'-amino-phenoxy-propionylamino)-1-ethane,
 1,2-di(2'-methyl-5'-amino-phenoxy-acetylamino)-ethane,
 1,4-di(alpha-ethyl-beta(3'-amino-phenoxy)-propionylamino)-4-methyl-3-ethyl-pentane,
 1,4-di(4'-amino-phenoxy-acetylamino)-cyclobutane,
 1,4-di(4'-amino-phenoxy-acetylamino)-2,5-dimethyl-cyclohexane,
 1,4-di(4'-amino-phenoxy-acetyl)-2-methyl-piperazine

and

1,4-di(4'-amino-phenoxy-acetyl)-2,5-dimethyl-piperazine

As the Y-NH₂ or coupling components indicated in the general formula the following are the classes:

(1) Arylamines of the benzene and naphthalene series represented by the formulae

wherein R' and m have the values heretofore defined, R'' is from the group consisting of hydrogen, alkyl, and alkoxy, k is 1 to 2 and the symbol —H denotes the coupling position.

(2) Amino naphthol sulfonic acids represented by the formula

in which one R''' is hydrogen and the other is hydroxy and the M' which is meta to hydroxy is —SO₃H and the other is hydrogen.

(3) Amino-phenyl-amino-naphthalene sulfonic acids represented by the formula

(4) Amino-benzoylamino-naphthalene sulfonic acids and amino-benzoylamino-benzoylamino-

naphthalene sulfonic acids represented by the formulae

and

(5) Amino phenyl pyrazolones represented by the formula

in which R''' is one of a group consisting of alkyl and carboxyl.

As illustrative of the many second components which can be used to produce the dyes having the characteristic structure and properties of those specifically described, the following are mentioned: 3-amino-anisole, 1-naphthylamine-6-sulfonic acid, 2-amino-5-naphthol-7-sulfonic acid, 2-(4'-amino-3'-sulfo-phenylamino)-5-naphthol-7-sulfonic acid, 2-(4'-amino-benzoylamino)-5-naphthol-7-sulfonic acid, 1-(3'-amino-phenyl)-5-pyrazolone-3-carboxylic acid, aniline, 3-amino-toluene, 2,5-dimethoxy-aniline, 2-methoxy-aniline, 2-methoxy-5-methyl-aniline, 1-amino-naphthalene, 1-amino-2-methoxy-naphthalene-6-sulfonic acid, 1-amino-naphthalene-6-carboxylic acid, 1,8-amino-naphthal-3,6-disulfonic acid, 2-amino-8-naphthol-3,6-disulfonic acid, 1-amino-8-naphthol-3,5-disulfonic acid, 1-amino-8-naphthol-4-sulfonic acid, 1-amino-5-naphthol-7-sulfonic acid, 2-amino-8-naphthol-6-sulfonic acid, 1-amino-5-naphthol, 2-(3'-amino-benzoylamino)-5-naphthol-7-sulfonic acid, 1-(4'-amino-benzoylamino)-5-naphthol-7-sulfonic acid, 2-(4'-amino-benzoylamino)-benzoylaminol-5-naphthol-7-sulfonic acid, 1-(4'-amino-benzoylamino)-8-naphthol-4-sulfonic acid, 1-(4'-amino-phenyl)-5-pyrazolone-3-carboxylic acid, 1-(3'-aminophenyl)-3-methyl-5-pyrazolone, 1-(4'-amino-phenyl)-3-methyl-5-pyrazolone, 1-(2'-methoxy-5'-amino-phenyl)-3-methyl-5-pyrazolone, 1-(4'-amino-3'-carboxy-phenyl)-3-methyl-5-pyrazolone, 1-(4'-amino-3'-sulfo-phenyl)-5-pyrazolone-3-carboxylic acid, 1-(2'-methyl-5'-amino-phenyl)-3-methyl-5-pyrazolone-3-carboxylic acid and 1-(2'-chloro-5'-amino-phenyl)-5-pyrazolone-3-carboxylic acid.

The substantive dyes contain at least two solubilizing groups such as carboxyl and sulfonic acid but more can be present.

As developing components 1-phenyl-3-methyl-

5-pyrazolone, metal-toluylene diamine or acetooacet anilide can be used as well as beta naphthol. These coupling components produce developed dyeings having similar superior fastness, discharge and brightness properties as those produced by developing with the beta naphthol and variations in shade can be attained by selection of the coupling component.

The first components of the azo compounds can be made by condensing a diamino alkane, a diamino-cyclo-alkane or a diaza-cyclo-alkane of the kinds described, such as a compound represented generally by the formula $\text{NH}_2-\text{D}-\text{NH}_2$ with a nitro acyl halide of the type

and then reducing the nitro groups of the di-nitro phenoxy acylamino)-alkane, -cyclo-alkane or -diaza-cyclo-alkane to amino. In general the condensation can be carried out readily at about 10° to 20° C. in the presence of a basic

condensing agent such as an alkali-metal hydroxide and in a medium comprising a non-reactive organic solvent, such as ethylene dichloride. The primary diamines formed after reduction of the nitro groups can then be separated and the products can be tetrazotized by methods which are in general well known in the art.

The tetrazotizable products are substantive to cotton, regenerated cellulose, various vegetable fibers and similar dyeable substances. When they are tetrazotized and developed on the fiber with the described azo dye coupling components they have excellent fastness to washing, they do not appreciably stain associated undyed fibers during washing and they have good general properties which are desirable in dyed fibers. When developed on the fibers the brightness of the dyeing is superior as compared with dyeings of like shade which are made with quite similar dyes which do not contain the phenoxy group. For example a dyeing on cotton made with 1,2-di(4'-amino-phenoxyacetylamine) - ethane and developed with beta naphthol is brighter than one made on cotton with 1,2-di(4'-aminobenzoyl-amino) - ethane and developed with beta naphthol.

This is a division of my application Serial No. 342,289.

From the foregoing disclosure it will be recognized that the invention is susceptible of modification without departing from the spirit and scope thereof and it is to be understood that the invention is not restricted to the specific illustrations thereof herein set forth.

I claim:

1. An azo compound represented by the formula

in which D represents a radical of the group consisting of the polymethylene diamines having 2 75

to 10 methylene groups and the straight and branched chain alkyl derivatives thereof in which alkyl has 1 to 6 carbons and in which the methylene groups are substituted once to twice the number of methylene groups, a radical of the diamino-cyclo-alkane series having 4 to 6 carbons in the ring and the mono- and di-methyl derivatives thereof, and a radical of the diaza-cyclo-alkane series having 3 to 6 carbons in the ring and the mono-di-methyl derivatives thereof; n is 1 to 6; each R' is from the group consisting of hydrogen, alkyl having 1 to 6 carbons, the corresponding alkoxy groups, halogen, CN, carboxy and sulfonic acid; m is 1 to 4; and each Y is the radical of a coupling component from the group consisting of arylamines of the benzene and naphthalene series, amino naphthol sulfonic acids, amino-phenyl-amino-naphthol sulfonic acids, amino-benzoylamino-naphthol sulfonic acids, amino-benzoylamino-benzoyl-amino-naphthol sulfonic acids and amino-phenyl pyrazolones; and each E is the radical of one of a group consisting of 1-phenyl-3-methyl-5-pyrazolone, meta-toluylene diamine, acetoacet anilide and beta naphthol.

2. An azo compound represented by the formula

in which D represents a radical of the group consisting of the polymethylene diamines having 2 to 10 methylene groups and the straight and branched chain alkyl derivatives thereof in which alkyl has 1 to 6 carbons and in which the methylene groups are substituted once to twice the number of methylene groups, a radical of the diamino-cyclo-alkane series having 4 to 6 carbons in the ring and the mono- and di-methyl derivatives thereof, and a radical of the diaza-cyclo-alkane series having 3 to 6 carbons in the ring and the mono- and di-methyl derivatives thereof; n is 1 to 6; each R' is from the group consisting of hydrogen, alkyl having 1 to 6 carbons, the corresponding alkoxy groups, halogen, CN, carboxy and sulfonic acid; m is 1 to 4; each Y is the radical of a coupling component of the benzene and naphthalene series from the group which is represented by the following formulae

---

N. N. N. N. N. D.

15

20

25

and

30

35

wherein R'' is one or any combination of the group consisting of hydrogen, alkyl having 1 to 6 carbons, and the corresponding alkoxy groups; k is 1 to 2; the symbol -H denotes the coupling position; one R''' is hydrogen and the other is hydroxy; the M which is meta to hydroxy is $-\text{SO}_3\text{H}$ and the other is hydrogen; and R''' is one of a group consisting of alkyl having 1 to 6 carbons and carboxyl; and each E is the radical of one of a group consisting of 1-phenyl-3-methyl-5-pyrazolone, meta-tolylene diamine, acetoacet anilide and beta naphthol; said compound having at least two solubilizing groups.

3. An azo compound represented by the formula

45

50

70

in which D represents a radical of the group consisting of the polymethylene diamines having 2 to 10 methylene groups and the straight and branched chain alkyl derivatives thereof in which alkyl has 1 to 6 carbons and in which the methylene groups are substituted once to twice the number of methylene groups, a radical of the diamino-cyclo-alkane series having 4 to 6 carbons in the ring and the mono- and di-methyl derivatives thereof, and a radical of the diaza-

75

cyclo-alkane series having 3 to 6 carbons in the ring and the mono- and di-methyl derivatives thereof; n is 1 to 6; each R' is from the group consisting of hydrogen, alkyl having 1 to 6 carbons, the corresponding alkoxy groups, halogen, CN, carboxy and sulfonic acid; m is 1 to 4; and each Y is the radical of a coupling component of the benzene and naphthalene series from the group which is represented by the following formulae

and

5 wherein R'' is one or any combination of the group consisting of hydrogen, alkyl having 1 to 6 carbons, and the corresponding alkoxy groups; k is 1 to 2; the symbol H denotes the coupling position; one R'' is hydrogen and the other is hydroxy; the M which is meta to hydroxy is -SO₃H and the other is hydrogen; and R''' is one of a group consisting of alkyl having 1 to 6 carbons and carboxyl.
